UNITED STATES PATENT OFFICE.

JAMES JARVIS PREBLE, OF NEWTON, MASSACHUSETTS; LIVINGSTON STEBBINS, ADMINISTRATOR OF SAID JAMES JARVIS PREBLE, DECEASED, ASSIGNOR TO SPRACO, INC., OF SOMERVILLE, MASSACHUSETTS, A CORPORATION OF MASSACHUSETTS.

AIR COOLING AND CLEANING APPARATUS.

Application filed March 27, 1923. Serial No. 629,153.

My invention relates to air washing and cooling apparatus for use with structures to be cooled, being particularly adapted for conditioning the ventilating air of electrical machinery.

In order that the principle of my invention may be readily understood I have disclosed certain illustrative embodiments thereof in the accompanying drawings 10 wherein:

Fig. 1 is a view partly in side elevation and partly in vertical section of an apparatus embodying my invention as adapted for use in connection with dynamo-electric 15 machines;

Fig. 2 is a vertical section upon an enlarged scale of the upper part of the central chamber, taken at right angles to the view shown in Fig. 1, the parts being shown in 20 normal operating positions;

Fig. 3 is a view similar to Fig. 2 but with the parts in their emergency position;

Fig. 4 is a vertical section of a modified 25 form of damper, and control mechanism therefor;

Fig. 5 is a view similar to Fig. 4 with the parts in their emergency position.

Fig. 6 is a view similar to Fig. 1 of an 30 apparatus including the form of damper shown in Figs. 4 and 5.

Referring more particularly to the drawings in Fig. 1 I have shown at 1 the casing of a dynamo-electric machine or generator, the stationary parts of which are indicated 35 generally at 2. Said dynamo-electric machine is supported in any suitable manner as by the concrete foundation represented at 3.

Preferably beneath the generator and approximately centrally thereof is positioned 40 the air washing and cooling apparatus. Said apparatus includes a central upright compartment providing a lower or spray chamber 4 and an upper chamber 5 in communication with the exhaust port 6 for the warm air from the generator. At either 45 side of said central compartment, and, as herein shown, at both sides are positioned vertical ducts 7 and 8 respectively for the return of the conditioned air to the generator in a closed circuit.

Within said spray chamber 4 and preferably at a position below the transverse median line thereof I provide a series of spray nozzles 9 arranged in one or more banks and

in communication with the fresh water supply pipe 10. Said nozzles 9, which may be of any preferred design, desirably are directed upwardly to spray water upwardly into the descending warm air from the generator. If desired, an additional row of 60 nozzles, one of which is indicated at 9' may be provided at each side of said spray chamber, directed inwardly and downwardly at an angle.

In each side wall of the spray chamber 4 65 adjacent the base thereof are located lateral exits 11 and 12 respectively, each provided with vertical eliminator plates 13 for removing any free moisture from the air returning to the generator. At the upper portion of said spray chamber and extending horizontally across the same is a series of baffle plates 14 for preventing any of the spray water from passing upwardly beyond the spray chamber and serving also to dis-

tribute the downwardly travelling air uniformly throughout said chamber. The circulation of air downwardly through the central compartment and upwardly through the side ducts 7 and 8 and through and about the generator within the casing 1, the warm air passing again to the central compartment through the generator casing outlets 6, 6 is maintained by fan blades 15 upon the generator rotor or, if desired, independent blower mechanism may be provided.

The structure above described constitutes 75 a closed circuit through which the same air passes continuously, being circulated and recirculated in the normal operation of the apparatus. The heat absorbed from the windings of the generator or from any other structure to be cooled is dissipated by

means of the liquid spray within the spray chamber 4. The air is constantly returned 80 to the generator at the necessary low temperature, usually not greater than 155° to 160° F.

If the air temperature should at any time 85 exceed a certain predetermined degree, approximately that just mentioned, great danger of injury to the generator would ensue. Such excess air temperature might occasionally rise from any one of a number

of causes. A heavy load upon the generator 90 often causes abnormal heating. Failure of, or low pressure in the spray water supply 95 would also result in heating of the air. A

similar result would follow from the use of spray water having an original temperature too high, or from a faulty regulation of the spray mechanism and in consequence insufficient supply of spray water for the load upon the machine.

Whatever the cause of the abnormal condition, the result in every instance is the excess heating of the ventilating air. It is therefore highly desirable to provide emergency air inlets and outlets whereby the apparatus may quickly be changed over from the enclosed circuit type above described to an open system in which outside air is supplied to the generator or other machine.

For this purpose I provide a system of emergency dampers which are adapted to function automatically whenever the temperature of the air in the closed circuit for any reason arises above a predetermined point. By means of said emergency dampers the closed circuit system may be immediately and automatically converted into an open system, and to an open system in which the fresh incoming air is first passed through the spray chamber where it is subjected to the cleaning action of the liquid spray.

In Figs. 2 and 3 I have represented upon an enlarged scale the upper chamber 5 of the central compartment. In the front and rear walls of said chamber, viewing Fig. 1 are provided emergency air inlet dampers 16, shown at the left in Figs. 2 and 3, and emergency air outlet dampers 17 seen at the right in said figures. Extending diagonally across chamber 5 between said inlet and outlet dampers is a third series of dampers 18 by which the downwardly flowing warm air may be shut off from the spray chamber. In the present instance I have shown said dampers as of the louver type but obviously my invention is not limited thereto.

The individual louvers of the inlet and outlet dampers are journaled by means of horizontal stud shafts 19, best seen in Fig. 1, in the opposite side walls 20, 21 of the upper chamber 5. Upon the outer face of each louver is rigidly secured an arm 22, the outer extremity of each of said arms being pivotally attached to connecting rods 23, 24 for the inlet and outlet dampers respectively. The louvers of the diagonal series of shut-off dampers 18 are similarly inter-connected by means of a connecting rod 25. The three series of dampers 16, 17 and 18 are also themselves inter-connected for simultaneous operation as by means of pivoted links 26 connecting the upper louvers of the inlet and the shut-off dampers, and the pivoted link 27 connecting the lower louver of the outlet dampers and a lower louver of the shut-off dampers.

The emergency dampers normally occupy the position shown in Fig. 2, the inlet damp-

ers 16 and outlet dampers 17 being closed, and the shut-off dampers 18 being in vertical or open position, allowing the warm air to travel directly to the spray chamber. Said dampers are releasably maintained in this position under normal operating conditions.

For that purpose I provide flexible means including a horizontal connecting cable 28 attached at one end to the lower extremity 75 of the connecting rod 24 for the outlet dampers 17 and passing upwardly over a pulley 29 suitably supported upon the adjacent wall of the central compartment. Said cable 28 then passes substantially horizontally across and within the chamber 5 and downwardly over a pulley 30 upon the opposite compartment wall. A spring 31 is desirably inserted in said cable at approximately its mid length. The opposite end 80 of cable 28 is secured to an operating cable 32, having a suitable handle 33 at its lower end. Said operating cable passes upwardly over pulley 34 and thence downwardly and is secured to the lower end of the connecting rod 23 for the inlet dampers 16.

At a suitable point upon the cable 28 within the chamber 5 is attached one end of an auxiliary cable 35 which extends horizontally to a point outside of said chamber 95 and over pulley 36, and is releasably secured to the lower louver of the inlet dampers 16, as by means of a hook 37. Inserted in that portion of said auxiliary cable 35 which extends within the chamber 5 is a fusible link 38 so positioned as to lie in the path of the warm exhaust air from the generator. Said link 38 may be of any suitable type designed to fuse and break at a predetermined temperature. Upon the lower end 100 of each of the connecting rods 23 and 24 are hung weights 39 and 39' respectively.

In the operation of the apparatus any air temperature above the desired pre-determined degree causes the link 38 to fuse, 110 thus breaking the auxiliary cable 35 and releasing the cable 28. The weights 39, 39' immediately drop, causing a downward movement of each end of cable 28, and effecting the instant opening of the inlet dampers 16 and outlet dampers 17 with the consequent simultaneous closing of the shut-off dampers 18. The warm exhaust air from the generator instead of passing downwardly through chamber 5 now exhausts directly out through the dampers 17 and to the right of Figs. 2 and 3. Fresh outside air enters through the inlet dampers 16 and passes downwardly through the spray chamber 4 and thence through the side ducts 7 115 and 8 to the generator.

When the cause of the excess heating of the air has been determined and remedied the dampers may readily be returned to their normal position. The auxiliary cable 130

35 is first released from hook 37. The attendant may then insert a new fusible link in the auxiliary cable 35. A downward pull upon the handle 33 of the operating cable 32 raises both weights 39, 39', closing the inlet and outlet dampers 16 and 17 and opening the shut-off dampers 18. The outer end of auxiliary cable 35 is then rehooked to the lower inlet louver, thus maintaining the weights in raised position and the dampers in their normal operating position shown in Fig. 2. Sufficient play in the cable 28 to permit said re-hooking of cable 35 is afforded by the provision of the spring 31.

In Figs. 1 to 3 I have shown emergency dampers of the louver type, which form is preferable in the larger installations of apparatus. Obviously, however, my invention is not limited to louver dampers since any suitable closure members may be employed so long as they function automatically upon the rupturing of a member which is fusible at air temperatures above a predetermined point and operate simultaneously to release the warm exhaust air to the atmosphere and to admit fresh outside air past the washer to the generator or other structure to be cooled.

In Figs. 4, 5 and 6 I have illustrated another embodiment of my invention, including closure members or emergency dampers of swinging door type, which are particularly adapted for use with apparatus of smaller dimensions than that shown in Figs.

1 to 3. The spray chamber is indicated at 4 and the warm air exhaust port of the generator or other structure at 6. It will be understood that in Figs. 4 to 6 all parts not specifically mentioned are similar to corresponding parts in Figs. 1 to 3. Hinged upon the front and rear walls of the central compartment at 40 and 41 respectively are an emergency inlet damper 42 and an emergency outlet damper 43, the inlet damper 42 being swingable upon an axis adjacent its upper edge and the outlet damper 43 being swingable about an axis at or near its lower edge. Extending diagonally across the chamber 5 is an angle iron 44 constituting a stop. Said dampers 42 and 43 in their open position as shown in Fig. 5 rest against the opposite sides of said stop 44 and together form a partition or shut-off to prevent the downwardly travelling exhaust air from entering the spray chamber 4 and causing it to pass immediately out to the atmosphere.

Said emergency dampers 42 and 43 may be operated by any suitable mechanism but preferably and as shown herein they are gravity actuated. For this purpose there is suspended upon the inlet damper 42 a weight 45 supported upon the outer end of a bracket 46 fixed upon the outer surface of said damper and suitably supported as by

means of braces 47. It will be observed that the outlet damper 43 has a downward swinging movement in travelling to its open position and accordingly tends to fall of its own weight. In order to assure the simultaneous movement of both dampers they are preferably inter-connected as by means of a flexible cable 48 fixed at one end to the inner face of damper 43 and passing over a roller 49, being secured at its other end to the bracket 46 upon the inlet damper 42.

The dampers are maintained in their normal closed position as shown in Fig. 4 by means of a cable 50 removably secured at one of its ends to the outer surface of the inlet damper 42 and passing over pulleys 51 and 52 suitably supported upon the front or left hand wall 40 of the compartment viewing Figs. 4 and 5 and thence within and across chamber 5 and over pulleys 53 and 54 on the opposite wall thereof, being secured at its opposite end upon the outer face of the outlet damper 43. Said cable 50 is preferably provided with a spring 55 at any suitable point in its length to permit necessary play in the operation of the cable. In that portion of said cable included within chamber 5 there is inserted a fusible link 56 which lies within the path of the warm air exhausted from the generator or other structure, said link being of the type shown in Figs. 2 and 3.

Whenever the exhaust air within the compartment exceeds the fusing point of said link 56 the cable 50 is ruptured, thus releasing the dampers which instantly move into the position shown in Fig. 5. The inlet damper 42 is swung inwardly and upwardly about its pivot by means of the weight 45 and the outlet damper 43 swings down and inwardly about its pivot due to its own weight. An initial jerk upon said damper 43 is afforded by the inter-connecting cable 48 assuring the opening of the same.

When the abnormal condition causing the excess air temperature has been remedied the dampers may be readily returned to their normal position by a downward pull upon the handle 57 at the lower end of the operating cable 58 which passes over a pulley in axial alignment with pulley 52 and is secured to the outer face of the damper 42 near the bottom edge thereof. An additional inter-connecting cable 59, secured upon the inner face of the damper 42, as at 60, passes over horizontally spaced pulleys 61 and 62, the latter upon an arm 63 projecting from the compartment, and is secured upon the outer face of the damper 43 as at 64.

Through said inter-connecting operating cable 59 downward movement of the inlet damper 42 by pull upon said operating handle 57 causes an upward return movement of the damper 43. In this manner

the single operating means 57 through said cables 58 and 59 simultaneously moves both dampers. To reset the dampers for normal operation that end of cable 50 which is removably secured to damper 42 is first released. The attendant then inserts a new fusible member 56, re-uniting the two portions of cable 50. The dampers are then closed by a downward pull upon the operating handle 57, and the cable is again secured to damper 42, thus holding the dampers in their normal closed position as shown in Fig. 4.

While the above described apparatus embodying my invention is particularly advantageous for conditioning the ventilating air for dynamo-electric machines it is not limited to such application but is adapted for general use with structures to be cooled. Said apparatus need not necessarily be located directly beneath the structure to be cooled although such position is preferred when practicable; in some instances, where space available for installation renders it desirable, the apparatus may be otherwise positioned, as for example, to one side of the structure to be cooled. Also, if desired, the direction of air flow in the inner and outer compartments may be reversed, and the direction and location of the spray nozzles correspondingly altered.

Having thus described my invention I desire it to be understood that I am not limited to the particular illustrative embodiments disclosed herein, the scope of the invention being set forth in the following claims:

1. Air cooling and cleaning apparatus for use with structures to be cooled comprising in combination a compartment communicating with said structure, one or more air ducts connected with said compartment, said ducts and said compartment together with said structure forming a closed circuit for the circulation and recirculation of air, means for cooling and cleaning the air flowing in said circuit, a series of emergency dampers operable to admit outside air into said circuit for travel past said cooling and cleaning means to the structure and to cause the warm air to be exhausted outwardly from the circuit, inter-connecting means including a fusible link for maintaining said dampers in normal position in which the air is recirculated, and means for operating said dampers upon fusing of said link.

2. Air cooling and cleaning apparatus for use with structures to be cooled comprising in combination a compartment communicating with said structure, one or more air ducts connected with said compartment, said ducts and said compartment together with said structure forming a closed circuit for the circulation and recirculation of air, means for cooling and cleaning the air flow-

ing in said circuit, a series of gravity-actuated dampers simultaneously operable to admit outside air into said circuit and to cause the warm air to be exhausted outwardly therefrom, and flexible connections, including a member fusible at a predetermined air temperature, for maintaining said dampers in normal position to recirculate the air.

3. Air cooling and cleaning apparatus for use with structures to be cooled comprising in combination, air conduits connected with the structure to be cooled in a closed circuit including said structure, means for circulating and recirculating the air in said circuit, means for cooling and cleaning the air in said circuit, closure members normally in position maintaining said closed circuit, and operable to convert said closed circuit into an open circuit receiving outside air and exhausting the warm air, mechanism including a member fusible at a predetermined air temperature for maintaining said closure members in normal position, and means for operating said closure members upon the fusing of said fusible member.

4. Air cooling and cleaning apparatus for use with structures to be cooled comprising in combination, air conduits connected with the structure to be cooled in a closed circuit including said structure, means for circulating and recirculating the air in said circuit, means for cooling and cleaning the air in said circuit, closure members normally in position maintaining said closed circuit and operable to admit outside air into the circuit and to cause the warm air to be exhausted therefrom, interconnections including a fusible link for maintaining the closure members in said normal position, and means for operating said closure members upon the fusing of said link.

5. Air cooling and cleaning apparatus for use with structures to be cooled comprising in combination a closed circuit for the circulation and recirculation of the air, said circuit including said structure, means for cooling and cleaning the air in said circuit, air inlet and outlet dampers, weights for moving said dampers, a cable normally maintaining said dampers in closed position, and a member having a predetermined fusing point for releasing said cable to permit movement of the dampers.

6. Air cooling and cleaning apparatus for use with structures to be cooled comprising in combination a warm air chamber, a cooling and cleaning chamber communicating therewith, one or more return air ducts connected with said spray chamber, said chamber and ducts together with said structure constituting a closed circuit for the circulation and recirculation of air, a series of dampers for said warm air chamber normally positioned to permit said recircula-

- tion of air and operable to convert said closed circuit into an open circuit receiving outside air, means including a fusible link for maintaining said dampers in said normal position and means for operating said dampers upon fusing of said link.
7. In a closed circuit apparatus for conditioning the ventilating air of electrical machinery, said circuit including said machinery, air-conditioning means in said circuit, a plurality of emergency dampers operable to permit the air to recirculate in said circuit or to admit outside air to the circuit, interconnections including a fusible member maintaining said dampers in normal position to permit said recirculation of the air and means mechanically connected to said dampers for automatically operating said dampers upon the fusing of said fusible member.
8. In a closed circuit apparatus for conditioning the ventilating air of electrical machinery, said circuit including said machinery, air-conditioning means in said circuit, a plurality of emergency dampers, inter-connections including a fusible link maintaining said dampers in normal position to permit the circulation and recirculation of air in said circuit, gravity-actuated means for simultaneously moving said dampers to reverse positions upon the fusing of said link thereby to admit outside air to said circuit and to cause the warm air to be exhausted outwardly therefrom, and means for simultaneously returning said dampers to normal position.
9. Air cooling and cleaning apparatus for use with structures to be cooled comprising in combination a compartment communicating with said structure, one or more air ducts connected with said compartment, said ducts and said compartment together with said structure forming a closed circuit for the circulation and recirculation of air, means for cooling and cleaning the air flowing in said circuit, swingable dampers upon opposite walls of said compartment normally in closed position and adapted to be swung inwardly into substantially the same plane transversely of said compartment to constitute a shut-off damper, and means mechanically connected to said dampers responsive to excess air temperatures in said compartment for automatically swinging said dampers.
10. Air cooling and cleaning apparatus for conditioning the ventilating air of electrical machinery comprising in combination a compartment communicating with said structure, one or more air ducts connected with said compartment, said ducts and said compartment together with said structure forming a closed circuit for the circulation and recirculation of air, means for cooling and cleaning the air flowing in said circuit, horizontally pivoted dampers upon opposite walls of said compartment normally in closed position and movable inwardly toward each other to form a partition transversely of said compartment, inter-connecting means including a fusible member for maintaining said dampers in said normal closed position, and automatic gravity-actuated means mechanically connected to said dampers for automatically moving said dampers upon fusing of said fusible member.
11. Air cooling and cleaning apparatus for use with structures to be cooled comprising in combination, air conduits connected with the structure to be cooled in a closed circuit including said structure, means for circulating and recirculating the air in said circuit, means for cooling and cleaning the air in said circuit, a pair of opposed pivoted closure members normally in closed position and operable to admit outside air into the circuit and to cause the warm air to be exhausted therefrom, interconnecting means including a fusible member for maintaining said closure members in their normal closed position, and means for operating said closure members upon fusing of said fusible member.
12. Air cooling apparatus for use with structures to be cooled comprising in combination air conduits connected with the structure to be cooled in a closed circuit including said structure, means for circulating and recirculating the air in said circuit, air cooling means in said circuit, closure members normally in position maintaining said closed circuit and operable to convert the same into an open circuit receiving outside air for circulation to said structure via said cooling means and exhausting the warm air unconditioned and interconnections including a fusible member for maintaining the closure members in said normal position but permitting them to be operated automatically in response to abnormal air temperatures.

In testimony whereof, I have signed my name to this specification.

JAMES JARVIS PREBLE.
